UNITED STATES PATENT OFFICE.

ERSKINE RAMSAY, OF BIRMINGHAM, ALABAMA.

ROLLER SUPPORT FOR ROTARY DUMPS.

Application filed September 6, 1927. Serial No. 217,819.

My invention relates to rotary car dumping apparatus, more particularly to the supporting means for such apparatus, and has for its object the provision of an improved roller support upon which the dump is adapted to rotate as it operates.

More specifically, the object of my invention is to provide an improved roller support including rollers having bearing portions of different diameters whereby a relatively wide angular movement of the part of greater diameter may be obtained with respect to the angular movement of the part of smaller diameter.

It has been the practice heretofore to provide rotary dumps with riding rings which were supported either upon rollers mounted on a fixed axis, or upon rollers resting on a track or support and having both bodily and angular movement responsive to the rotation of the riding ring. My present invention relates more particularly to the latter class of roller supports and its prime object is to reduce to a minimum the travel of the roller support and to simplify and perfect the track elements both on the roller support and on the riding ring of the rotary dump with which the rollers co-act. In order to reduce the lineal travel of the rollers, I provide a differential roller having its larger diameter portion co-acting with the rotary dump and its smaller diameter portion co-acting with the fixed track or support, whereby wide peripheral travel of the large diameter riding rings is reduced to a very small lineal travel of the roller on its track supports.

My invention further contemplates so designing the differential roller and its track supports that it is balanced in its work and will serve to hold the riding ring of the dump in correct position centrally above the track.

My invention further contemplates the designing of both the track supports and the riding ring of the dump and the working surfaces of the differential roller so that all are protected by case hardened steel, thereby providing great durability.

Apparatus embodying features of my invention is illustrated in the accompanying drawings forming a part of this specification, wherein

Fig. 1 is an end elevation of a rotary dump provided with my improved roller supports.

Fig. 2 is a view in side elevation of the dumping apparatus partly broken away.

Fig. 3 is a detailed sectional view taken along the line III—III of Fig. 1 and showing one of my improved roller supports; and

Fig. 4 is a detailed view showing, in elevation, one of the track elements employed with my invention.

Referring to the drawings, I show framework including upright members 10 and transverse members 11 and 12, the framework forming a support for the rotary car dumping apparatus. The cars to be dumped move into the rotary dumping apparatus from a track 13 onto a track 14. The track 14 is supported by riding rings 16, arranged at intervals to accommodate a suitable number of cars, in the example shown in Fig. 2, two cars, 17 and 18.

As is well understood in the art to which my invention relates, the cars 17 and 18, upon being placed on the track 14, are bodily rotated by means of the rotation of the dump so that their contents are dumped by gravity out of the cars into suitable hoppers indicated generally at 21. The dump may be operated by gravity or by suitable means such as chains 22 extending partly around and secured at one end to the ring and carried by pulleys 23 and 24, the pulleys 23 being supported from longitudinal members 26, and the chain 22 being operated by any suitable mechanism, not shown or described in detail as same forms no part of my present invention.

The riding rings 16 are each comprised of plate members 27 and 28 joined together by a circular channel member 29, as by rivets 31 and 32. The circular channel member 29 forms a bearing member for the rings 16 when it is rotated. The channel member 29 rests upon my improved roller bearing which includes roller members 33 and 34, said members being supported, in turn, by a segmental track or race comprised of parallel tracks each formed by the members 36 and 37, a pair of similar members being arranged at opposite ends of the segment. The track members 36 and 37 are supported by the transverse members 12.

The bearing members 33 and 34 are made of case hardened steel and are provided with axle portions 38 resting on the parallel track members 36 and 37, and with body portions 33 or 34 of greater diameter than the axle portions 38, and depending between the track members 36 and 37. The circular channel member 29 of the rings 16 rests upon the body portions 33 or 34 and in order to minimize

wear of both the rings and the bearings, is provided with a track 41, preferably made of case hardened steel, and extending around the channel member to form a bearing surface therefor.

The bearing members 33 and 34 are maintained in spaced relation by means of a segmental frame comprised of similar front and rear frame members 46 and 47. The members 46 and 47 are provided with holes 48 and 49 to accommodate pins 51 and 52 extending through the holes and through suitable holes provided in the axle portions 38 of the bearings. The pins 51 and 52 are held in place with respect to the bearing by means of plates 53 secured to the member 46 by cap screws 54 and extending into suitably formed notches in the pins 51 and 52. The members 46 and 47 are held properly spaced by means of a pair of short channels 56 and 57 arranged near the opposite ends of the members. It will be seen from a consideration of Fig. 1 that the members 46 and 47 hold the bearings 33 and 34 in properly spaced relation at all times.

The travel of the bearings is limited at each end of the track by means of a curved stop 61 formed at the upper end of each of the track members, so that when either of the bearings reaches the stop, its axle portions are engaged thereby and it is prevented from further travel. The spacing of the bearings 33 and 34 and the arrangement of the stops 61, as will be seen from Fig. 1, are such that the bearings are at all times disposed on opposite sides of the central vertical plane passing through the riding rings 16.

In order to protect the bearings 33 and 34 and the tracks 36 and 37 from being clogged with material when the cars are being dumped, I provide the members 46 and 47 with inwardly extending lip portions 63 and 64. It will be seen, when the cars are being dumped, that material falling from the cars in the direction of the bearings 33 and 34 would be deflected by the lip portions 63 and 64.

From the foregoing description, the operation of the apparatus made in accordance with my invention will be apparent. Upon rotation of the riding rings 16, when dumping the cars, the bearings 33 and 34 are rotated by their contact with the riding rings 16. Inasmuch as the axle portions 38 of the bearings bear upon the tracks 36 and 37, the lineal movement of the bearings is obviously much less than that of the rings 16. Assuming that the rings 16 are to be rotated to the left, as shown by the arrow in Fig. 1, a rotation of approximately 180 degrees thereof will only cause the bearings to move until the axle portion of the bearing 34 is engaged with the stop 61.

The advantages of the hereinbefore described construction will be clearly appreci-

ated in that it affords a bearing support remarkably free from friction, and hence having a long life, and one which insures a proper support for the riding ring, whatever the angular movement of the dump.

While I have shown my invention in but one form, it will be obvious to those skilled in the art that it is not so limited, but is susceptible to various changes and modifications, without departing from the spirit thereof, and I desire, therefore, that only such limitations shall be placed thereupon as are imposed by the prior art or as are specifically set forth in the appended claims.

Having thus described my invention, what I claim as new and desire to secure by Letters Patent, is:—

1. In apparatus of the character described, a riding ring, a segmental track arranged beneath the ring, a plurality of movable roller bearings on the track and supporting the ring and adapted upon angular movement of the ring to roll along the track, said bearings each having an axle portion bearing on the track and a body portion supporting the ring, the body portion being of greater diameter than the axle portion.

2. In apparatus of the character described, a movable roller bearing including members having axle bearing portions and body bearing portions, the axle bearing portions differing in diameter from the body bearing portions, a segmental track of said members and co-acting with the axle portions, and a riding ring supported by the body portions and rotatable thereon.

3. In apparatus of the character described, a roller bearing including members having axle portions and body portions, the body portions being greater in diameter than the axle portions, a frame for the bearing members maintaining them in predetermined spaced relation, a segmental track for the bearing members and co-acting with the axle portions thereof, rotary dump mechanism supported by the body portions; and means for limiting lineal movement of the bearing members on the track to cause them to lie on opposite sides of the vertical central plane of the rotary dump mechanism.

4. In apparatus of the character described, a movable roller bearing including rollers having axle portions and body portions, the axle portions being smaller in diameter than the body portions and extending outwardly from the body portions, a segmental track comprising parallel members supporting the axle portions and spaced apart to provide a recess for the body portions, and rotary dump mechanism supported by the body portions.

5. In apparatus of the character described, a roller bearing including a plurality of movable members having axle portions and body portions differing in diameter, means for maintaining

the movable members in predetermined spaced relation, a segmental track for the members and co-acting with the axle portions thereof, rotary dump mechanism supported by the body portions, and means provided on the track for limiting linear movement of the movable members.

6. In apparatus of the character described, a segmental track embodying a pair of parallel rail members, a plurality of movable roller bearing members on the track, said bearing members each having axle portions riding on the parallel rails and a body portion interposed between the axle portions and de-

pending between the parallel rails, a rotary 15 riding ring resting on the body portions, frame members for maintaining the bearing members in predetermined spaced relation and including shield means for protecting the bearing members and the track, and means for 20 limiting movement of the rollers along the track whereby they provide supports for the riding ring on opposite sides of the central vertical plane thereof in all positions of said ring.

25 In testimony whereof I affix my signature.

ERSKINE RAMSAY.
